CLAIM

The ornamental design for medical dressing as shown and described.

DESCRIPTION

FIG. 1 is a top, front, right perspective view of a first embodiment of a medical dressing showing our new design; FIG. 2 is a top plan thereof; FIG. 3 is a bottom plan thereof; FIG. 4 is a left side front elevational view thereof; FIG. 5 is a right side elevational view thereof; FIG. 6 is a front elevational view thereof; FIG. 7 is a rear elevational view thereof; FIG. 8 is a bottom, left, rear perspective view thereof; FIG. 9 is a top, front, right perspective view of a second embodiment of a medical dressing showing our new design; FIG. 10 is a top plan thereof; FIG. 11 is a bottom plan thereof; FIG. 12 is a left side elevational view thereof; FIG. 13 is a right side elevational view thereof; FIG. 14 is a front elevational view thereof; FIG. 15 is a rear elevational view thereof; and, FIG. 16 is a bottom, left, rear perspective view thereof. In the drawings, same sized broken lines depict elements on the medical dressing that form no part of the claimed design.
